CLARIFIER

Johann Joseph Stoeckly, Teltow-Seehof, Germany, assignor to North American Rayon Corporation, New York, N. Y., a corporation of Delaware

Application April 3, 1936, Serial No. 72,470
In Germany April 11, 1935

3 Claims. (Cl. 210—52)

This invention relates to improvements in clarifiers such as are used in the industry for the purification of lyes, oils and the like, i. e., liquids which deposit solids or slimy substances, and which are usually provided with a conical mud repository in which the sediment may settle and from where the said sediment may be drawn off by any suitable means.

The discharge pipe for the purified liquid is preferably arranged above the mud repository. In most cases the outlet pipe leads directly to the discharge pump which pumps the purified liquid to the points of consumption or storage. During the starting and stopping of these pumps, impulses in the connecting pipe in the direction toward the clarifier, and consequently whirling motions in the clarifier are almost inevitable. Every whirl in the liquid within the clarifier disturbs the normal purifying process and causes a portion of the sediment to be drawn off together with the purified liquid.

In order to overcome the above mentioned disadvantage, it has been suggested to arrange below the clarifier a second tank for the purified liquid and to discharge the purified liquid into this tank from time to time, from where it is then drawn off by the pump. This solution of the problem, however, requires the installation of a second tank of considerable size; the necessary new foundation required for this second tank is also an expensive item, and the entire arrangement necessitates an increase in the steps of operation and an increased power consumption for the elevation of the liquid.

It is therefore one object of the present invention to devise an improved clarifying arrangement which will overcome the aforesaid disadvantages of clarifiers now in use and will accomplish an improved purification of liquids containing sediment with a minimum of change and cost in installation. This and other objects of the present invention will in part become obvious and will in part be pointed out in the following specification and appended claims when taken in conjunction with the attached drawing in which is illustrated a diagrammatical cross-sectional view of the improved clarifying arrangement comprising the invention.

In accordance with the present invention, a standpipe is added to the clarifier, which is in communication with the latter above the mud repository. The standpipe which is approximately of the same height as the clarifier, is filled up to the water level of the clarifier by means of the connecting pipe. The actual outlet pipe which is

preferably connected with a pump by means of a valve is arranged in the lower end of the standpipe.

During the starting and stopping of the pump the liquid impulses caused thereby may possibly extend into the standpipe but such impulses have practically disappeared in the connecting pipe into the clarifier, so that the result of this arrangement is to leave the purified liquid in the clarifier practically undisturbed.

The arrangement of the new device is illustrated in the accompanying drawing, in which 1 indicates a clarifier which is provided at its upper end with a supply pipe 2, a discharge pipe 3, a cover 4 and a small access opening 5 provided therein. Besides, a special aerating and deaerating device may be provided.

The lower end 6 of the tank is conically formed and represents the so-called mud sack or mud repository in which the sediments settle; these sediments are from time to time removed by means of the valve 7 arranged at the bottom.

A connecting pipe 8 is positioned above the mud sack and is connected to the standpipe 9. It is preferred to provide the connecting pipe 8 with a valve 10.

The standpipe 9 possesses a separate discharge outlet 11 which is preferably arranged at the same level as the discharge outlet 3 of the clarifier 1 and which may also empty into the same discharge pipe 12. The standpipe 9 may also be provided with a cover 16.

The actual discharge pipe 13 for the purified liquid is positioned at the lower end of the standpipe 9. From this point the purified liquid is drawn off by the pump 15 through a valve 14.

During the first filling of the clarifier or during the refilling, i. e., whenever the contents of the clarifier is disturbed in its rest, the valve 10 may be closed and opened only after the liquid in the clarifier has come to rest again and the major portion of the sediment has settled.

The diameter of the standpipe is preferably in proportion to the diameter of the clarifier; for large clarifiers correspondingly large standpipes should be chosen, for example, a clarifier having a diameter of 3 meters should have a standpipe of a diameter of 50—60 centimeters.

It is to be understood that the form of the invention, herewith shown and described, is to be taken as a preferred example of the same, and that various changes in the shape, size and arrangement of parts may be resorted to, without departing from the spirit of my invention, or the scope of the subjoined claims.

Having thus described the invention as required by the patent statutes what I claim is:

- 5 1. In combination, a clarifier for liquids, a discharge pump therefore, means positioned between said clarifier and pump to absorb impulses in the flow of liquid from said clarifier to said pump, and pipe lines connecting said means with the clarifier and the pump.
- 10 2. In combination, a clarifier for liquids, a discharge pump therefore, a standpipe positioned between said clarifier and pump to absorb impulses in the flow of liquid from said clarifier

to said pump, and pipe lines connecting said standpipe with the clarifier and the pump.

3. In combination, a clarifier for liquids having a funnel-shaped bottom, a discharge pump therefor, a standpipe between said clarifier and said pump, said standpipe communicating with said clarifier at a point above the said funnel-shaped portion of the clarifier, and a pipe line connecting the lower end of said standpipe with said pump.

JOHANN JOSEPH STOECKLY.
